UNITED STATES PATENT OFFICE.

WILLIAM H. DE BUSK, OF CHICAGO, ILLINOIS, ASSIGNOR TO THE P & M COMPANY, OF CHICAGO, ILLINOIS, A CORPORATION OF ILLINOIS.

RAIL ANCHOR.

Application filed June 18, 1925. Serial No. 37,943.

To all whom it may concern:

Be it known that I, WILLIAM H. DE BUSK, a citizen of the United States, residing at Chicago, in the county of Cook and State 5 of Illinois, have invented certain new and useful Improvements in Rail Anchors, of which the following is a specification.

My invention relates to rail anchors of the type adapted, by engagement with a cross tie or other fixed portion of a roadbed, to hold a rail against movement longitudinally thereof, and it has for its principal object the provision of a new and improved form and arrangement of parts 10 by which a very simple, and at the same time a very strong and effective, anchor can be produced easily and at low cost.

It is one of the objects of my invention to provide in an anchor of this type a new 20 combination of parts comprising a clip of high grade metal adapted to grip the flange of the rail at one side thereof and improved means comprising a part or parts of comparatively low grade metal for holding the 25 clip in position on the rail. It is another object of my invention to provide improved means in an anchor of this type serving as the abutment for the anchor against the cross tie, whereby the weight and size of 30 the anchor may be kept at a minimum while at the same time providing a bearing of liberal size and ample strength.

It is another object of my invention to 35 improve devices of this type in sundry details hereinafter pointed out. The preferred means by which I have accomplished my several objects are illustrated in the drawing and are hereinafter specifically described. That which I believe to be new 40 and desire to cover by Letters Patent is set forth in the claims.

In the drawing,—

Fig. 1 is a face view of my improved 45 construction shown in position upon a rail which is illustrated in cross section, being partly broken away, the normal shape of the clip before its application to the rail being indicated by dotted lines.

Fig. 2 is a view similar to Fig. 1, but 50 showing a changed position of one of the parts in the course of the application of the anchor to the rail.

Fig. 3 is a fragmentary top view of the 55 parts shown in Fig. 1.

Fig. 4 is a view similar to Fig. 1 but

showing a modified form of construction; and

Fig. 5 is a fragmentary top view of the parts shown in Fig. 4.

Referring particularly to Figs. 1 to 3 60 inclusive, 10 indicates a railroad rail, supported in position upon a cross tie 11. 12 indicates a clip formed from a heavy bar or high grade metal bent into shape as indicated by the dotted lines in Fig. 1, being spread apart when driven from one side of the rail into position upon the flange as indicated. The clip 12 is to be applied to the flange of a rail at a short distance from the face of the tie as indicated in 70 Fig. 3, leaving room for the insertion of a retainer member 13. In its preferred form, the retainer member 13 is in the form of a plate of comparatively low grade metal 73 cut out at one side to receive the flange of the rail 10 and provided with an arm 14 extending across beneath the rail and provided with a lug 15 at its end portion adapted to engage the opposite edge of the flange of the rail. Adjacent to the clip 12, the 80 retainer 13 is provided with a flange 16 formed integrally therewith, adapted by engagement with the outer face of the clip 12 to hold the clip from backing transversely from the flange of the rail. 85

In the construction shown, the retainer member 13 is so shaped and proportioned that it is necessary to distort the retainer for application to the rail flange. In the operation of applying the retainer member, 90 it is first placed in position as indicated in Fig. 2 between the clip 12 and the cross tie 11, and it is then forced toward the left in Fig. 2 until the lug 15 snaps resiliently into engagement with the edge of the flange of the rail as indicated in Fig. 1. The retainer member 13 is preferably given its operative movement toward the left by a series of blows by a maul or hammer, although it can of course be otherwise forced 95 into position.

With the retainer member in position as indicated in Fig. 1, the plate forming the body of the member provides the abutment for the clip against the tie, the plate providing in effect an extension of the lower portion of the clip 12 for this purpose. As will be readily understood, even though the plate 13 is of comparatively low grade metal 105 and has in and of itself no considerable 110

strength or stiffness, such plate reenforced and backed up by the clip 12 forms a very effective abutment against the tie.

Referring now to Figs. 4 and 5, in which 6 a modified form of construction is illustrated, the construction is substantially the same as that above described, except that the metal of the retainer member 17 is very considerably thinner than that of the retainer member shown in Figs. 1, 2 and 3. In this construction, in order better to brace the device against the cross tie 11, I have provided an auxiliary plate 18 interposed between the body of the retainer member 10 17 and the clip 12. The plate 18 may be made of as heavy a construction as may be desired, being provided with a recess at the side to receive the flange of the rail 10, being adapted preferably to have a snug fit upon the top and bottom faces of the flange. If desired, the plate 18 may have a driving fit upon the flange of the rail. In the construction shown in Figs. 4 and 5, 15 the retainer member 17 is also provided with an inwardly turned flange 19 at the outer edge of the flange 20, the arrangement being such that the flange 20 is adapted to engage the outer edge faces of the plate 18 and the clip 12, while the flange 19 is adapted to 20 engage a very small portion of the side face of the clip 12. By this arrangement, the retainer member 17 is adapted to hold the plate 18 and the clip 12 together to better 25 advantage in operative position upon the rail.

For applying the anchor the clip 12 of the construction shown in Figs. 4 and 5, is first preferably driven upon the flange of the rail at a suitable distance from the tie 40 11, the plate 18 is then applied between the clip 12 and the cross tie, and the retainer member 17 is then driven into snap engagement with the opposite edge of the flange between the plate 18 and the cross tie 11.

45 By my construction, as illustrated in Figs. 4 and 5, I have provided a clip 12 which is of the weight and strength required for gripping the rail flange very strongly. The plate 18 is of a weight and strength for providing the desired extension of the bearing for the anchor against the cross tie. The retainer member 17 is of the required weight and strength merely for holding the plate 18 and the clip 12 from backing transversely from the flange of the rail. By this construction, I have provided an anchor which is very effective for preventing longitudinal movement of the rail, while at the same time the weight and the cost of the parts are kept to a minimum.

50 While I prefer to employ the construction as illustrated in my drawing, it will be understood that I do not desire to be limited to the precise construction illustrated except so far as the same may be

specifically claimed, inasmuch as it is evident that changes may well be made in the details of construction without departing from the spirit of my invention.

70 I claim:

1. A rail anchor comprising a clip adapted to be driven into gripping engagement with the flange of a rail from one side thereof and means adapted to have resilient snap engagement with the rail for holding the 75 clip in operative position on the flange, said means comprising a separately formed metal plate interposed in vertically extending position between the clip and the cross tie.

2. A rail anchor comprising a clip adapted 80 to be driven into gripping engagement with the flange of a rail from one side thereof, a plate interposed in vertically extending position between the clip and the cross tie serving to provide an extended bearing for 85 the clip against the tie, and means for holding said plate and clip against backing transversely from the rail.

3. A rail anchor comprising a clip adapted 90 to be driven into gripping engagement with the flange of a rail from one side thereof, a plate cut out at one side for embracing the flange of a rail between the clip and the cross tie and serving to provide an extended bearing for the clip against the tie, and means for holding said plate and clip against backing transversely from the rail.

4. A rail anchor comprising a clip adapted 100 to be driven into gripping engagement with the flange of a rail from one side thereof, a plate interposed in vertically extending position between the clip and the cross tie, serving to provide an extended bearing for 105 the clip against the tie, and means formed integrally with the plate for holding the plate and the clip against backing transversely from the flange of the rail.

5. A rail anchor comprising a clip adapted 110 to be driven into gripping engagement with the flange of a rail from one side thereof, a plate interposed in vertically extending position between the clip and the cross tie serving to provide an extended bearing for 115 the clip against the tie, means formed integrally with the plate and extending underneath the rail adapted by engagement with the opposite edge of the flange to hold the plate from backing transversely from the rail, and other means carried by the plate for holding the clip also from backing 120 transversely from the rail.

6. A rail anchor comprising a clip adapted 125 to be driven into gripping engagement with the flange of a rail from one side thereof, a plate interposed in vertically extending position between the clip and the cross tie serving to provide an extended bearing for the clip against the tie, means formed integrally with the plate and extending underneath the rail adapted by engagement 130

with the opposite edge of the flange to hold the plate from backing transversely from the rail, and a flange formed integrally with the plate adapted by engagement with the outer face of the clip to hold the clip also from backing transversely from the rail.

7. A rail anchor comprising a clip adapted to be driven into gripping engagement with the flange of a rail from one side thereof, a plate interposed in vertically extending position between the clip and the cross tie serving to provide an extended bearing for the clip against the tie, means formed integrally with the plate adapted by resilient snap engagement with the opposite edge of the flange of the rail to hold the plate against backing transversely from the rail, and other means carried by the plate for holding the clip also against backing transversely from the rail.

8. A rail anchor comprising a clip adapted to be driven into gripping engagement with the flange of a rail from one side thereof, a plate interposed in vertically extending position between the clip and the cross tie serving to provide an extended bearing for the clip against the tie, a resilient arm formed integrally with the plate and extending underneath the rail adapted by snap engagement with the opposite edge of the flange to hold the plate from backing transversely from the rail, and a flange formed integrally with the plate at its outer edge adapted by engagement with the outer face of the clip to hold the clip also from backing transversely from the rail.

9. A rail anchor comprising a heavy clip adapted to be driven into strong gripping engagement with the flange of a rail from one side thereof, and a second member in the form of a light plate extending in vertical position between the clip and the tie serving to provide an extended bearing for the clip against the tie and serving to hold the plate and the clip from backing transversely from the rail.

10. A rail anchor comprising a heavy clip of high grade metal adapted to be driven into strong gripping engagement with the flange of a rail from one side thereof, and a second member in the form of a light plate of low grade metal extending in vertical position between the clip and the tie serving to provide an extended bearing for the clip against the tie and serving to hold the clip in operative position on the rail.

11. A rail anchor comprising a heavy clip adapted to be driven into strong gripping engagement with the flange of a rail from one side thereof, a second member in the form of a light plate extending in vertical position between the clip and the tie and serving to hold the clip from backing transversely from the rail, and a third member in

the form of a plate extending in vertical position between the clip and the second member and serving to provide an extended bearing for the clip with respect to the tie.

12. A rail anchor comprising a heavy clip adapted to be driven into strong gripping engagement with the flange of a rail from one side thereof, a second member in the form of a light plate extending in vertical position between the clip and the tie and serving to hold the clip from backing transversely from the rail, and a third member in the form of a plate cut out at one side for embracing the flange of the rail between the clip and the second member and serving in connection with the second member to provide an extended bearing for the clip against the cross tie.

13. A rail anchor comprising a heavy clip adapted to be driven into strong gripping engagement with the flange of a rail from one side thereof, a plate cut out at one side adapted in vertically extending position to embrace the flange of the rail between the clip and the cross tie, and a third member in the form of a plate extending in vertical position between the first-named plate and the tie and serving to hold the clip and the first named plate from backing transversely from the rail.

14. A rail anchor comprising a heavy clip adapted to be driven into strong gripping engagement with the flange of a rail from one side thereof, a plate cut out at one side adapted in vertically extending position to embrace the flange of the rail between the clip and the cross tie, a third member in the form of a light plate extending in vertical position between the first-named plate and the tie and serving by snap engagement with the opposite edge of the flange of the rail to resist transverse movement from the rail, and means carried by said second plate adapted also to hold the first named plate and the clip in operative position on the flange.

15. A rail anchor comprising a heavy clip adapted to be driven into strong gripping engagement with the flange of a rail from one side thereof, a plate cut out at one side adapted in vertically extending position to embrace the flange of the rail between the clip and the cross tie, a third member in the form of a light plate extending in vertical position between the first-named plate and the tie and serving by snap engagement with the opposite edge of the flange of the rail to resist transverse movement from the rail, and a flange formed on the second plate adapted by engagement with the outer faces of the first named plate and the clip to hold them in operative position on the flange.

16. A rail anchor comprising a heavy clip adapted to be driven into strong gripping engagement with the flange of a rail from

- one side thereof, a plate cut out at one side adapted in vertically extending position to embrace the flange of the rail between the clip and the cross tie, a third member in the form of a light plate extending in vertical position between the first-named plate and the tie and serving by snap engagement with the opposite edge of the flange of the rail to resist transverse movement from the rail, and a flange formed on the second plate and extending about the outer edge faces of the first named plate and the clip and a short distance along the side face of the clip adapted to hold the several members of the anchor together in operative position on the flange.
17. A rail anchor comprising a clip adapted to be driven into gripping engagement with the flange of a rail from one side of the rail, and means for holding the clip in operative position on the flange comprising a separately formed plate interposed in vertical position between the clip and the cross tie.
18. A rail anchor comprising a clip adapted to be driven into gripping engagement with the flange of a rail from one side of the rail, and a plate interposed in vertically extending position between the clip and the cross tie, serving to provide an extending

bearing for the clip against the tie and provided with a jaw adapted to be driven into gripping engagement with the rail base.

19. A rail anchor comprising a clip adapted to be driven into gripping engagement with the flange of a rail from one side thereof, and means for holding said clip from backing transversely from the rail, comprising a rail base embracing member formed with a jaw for engaging the upper surface of the rail base adjacent said clip and provided with a portion extending vertically between said clip and the cross tie.

20. A rail anchor comprising a clip member adapted to be driven into gripping engagement with one flange of a rail base, and means serving to provide an extended bearing for said clip against the tie, comprising a rail gripping member adapted to be driven into gripping engagement with said base flange adjacent said clip.

21. A rail anchor comprising a plurality of separately formed clip members, formed with rail gripping jaws, and adapted to be driven adjacent each other into gripping engagement with one flange of a rail base, one of said members being formed to provide an extended abutment for an adjacent clip member.

WILLIAM H. DE BUSK.
